United States Patent Office

Des. 195,526
Patented June 25, 1963

195,526

PITCHER

James D. Wallner, 1718 W. Collum Ave., Chicago, Ill.

Filed Jan. 26, 1962, Ser. No. 68,529

Term of patent 7 years

(Cl. D44—21)

Fig. 1.

FIG. 1 is a perspective view of a pitcher embodying the design of this invention;

FIG. 2 is a plan view of the pitcher of FIG. 1; and
FIG. 3 is a front elevational view of the pitcher of FIG. 1 looking toward the right in FIG. 1.

I claim:

The ornamental design for the pitcher, as shown.
